UNITED STATES PATENT OFFICE

MILES F. DEACH, OF OAKLAND, CALIFORNIA

ADJUSTABLE LAMP SUPPORT

Application filed May 31, 1927. Serial No. 195,376.

My invention relates to a portable light supporting structure of the adjustable type, and particularly to a structure arranged for use as a garage lamp.

5 An object of the invention is to provide a lamp of the class described having the parts thereof arranged for a maximum of adjustment.

10 Another object of the invention is to provide in a device of the character described a novel and particularly efficient adjustable mounting of a swing-arm bracket forming a part of the device.

15 The invention possesses other objects and features of advantage, some of which, with the foregoing, will be set forth in the following description of the preferred form of the invention which is illustrated in the accompanying drawings and in which, Figure 1 is 20 an elevation of the complete structure.

Figure 2 is a generally diagrammatic plan view at a reduced scale and having indicated thereon different possible adjustments of the device.

25 Figure 3 is an elevation illustrating the positioning of the parts for casting light on the under surface of an overhanging.

Figure 4 is a sectional plan view taken on the line 4—4 in Figure 1, the view being 30 drawn to an enlarged scale.

Figure 5 is a sectional view taken on the line 5—5 in Figure 4, and

Figure 6 is a side view of a portion of the structure of Figs. 4 and 5.

35 As herewith particularly shown, the device of my invention comprises a weighted base member 7 having a cylindrical stem or standard 8 extending upwardly therefrom and on which is mounted a swing-arm bracket 9 carrying an electric light socket 11 at the outer extremity thereof. The socket 11 is preferably arranged for a maximum of adjustment with respect to the bracket end which carries it, and as here shown is carried at an 40 extremity of a rod 12 longitudinally and rotatably adjustable in a member 13. The member 13, it will be noted is carried at the end of an upwardly extending post or strut 14 swivelled to the arm 9 and is arranged to permit the angular adjustment of rod 12 about

an axis perpendicular to that of the post 14. In this manner, the rod is arranged to be adjustably set to dispose the light in any desired relation to the extremity of arm 9 within the limits imposed by the length of the rod 12, 55 it being noted that the particular means herewith disclosed in mounting the lamp fixture on the arm 9 is the subject matter of my United States Patent No. 1,714,003, dated May 21, 1929.

60 The arm 9, it will now be noted, is forked at its inner end to provide generally parallel spaced portions 16 and 17 having their opposed face portions 18 and 19 respectively 65 parallelly related. The portions 16 and 17 are provided with axially aligned perforations 29 and 30 having their axial line perpendicular to the surfaces 18 and 19 of the portions, and such perforations are of a size to rotatably receive the standard 8. It will now 70 be obvious that under static conditions, the weight of the arm and lamp portion supported thereby would, when the bracket is mounted on the standard, tend to hold the arm in set position on the standard when the latter 75 is erect by reason of the lateral bearing of the spaced arm portions against the standard. But since, in a lamp of the class described, a swinging of the arm about the standard is frequently desirable, and such swinging 80 would tend to effect a simultaneous downward movement of the arm along the standard, means are provided for positively holding the arm at an adjusted height on the standard and at the same time permitting its 85 swinging therearound.

90 In the present embodiment of the invention, the fixing of the bracket arm 9 at a desired adjusted position along the standard 8 is arranged to be effected by means of a collar member 21 arranged to be disposed about the standard between the arm portions 16 and 17 and to be releasably fixed to the standard by means of a set screw 22 extending through the member 21 and arranged to be projected against the standard for locking the member 21 thereto. As here shown, the set screw 22 is provided at its outer end with a winged head 23 for facilitating the manipulation thereof. Preferably, means are provided in 100

association with the member 21 for frictionally engaging both of the arm surfaces 18 and 19 simultaneously. Accordingly, the member 21 is provided at one end thereof with a 5 radially extending flange 24 and is encircled at the other end by a ring member 25 having substantially the same outer diameter as the flange 24. Operatively interposed between the flange 24 and ring 25 to encircle the intermediate portion of the member 21 is a compressed helical spring 26, such spring being arranged to react between the flange and ring to resiliently and frictionally engage the flange end of the member 21 and such ring 10 against the surfaces 18 and 19 respectively of the arm. In this manner, a frictional holding of the arm in set position is provided, yet the arm may be swung to a new position without involving any manipulation of set screws or 15 the like.

Preferably, rotation of the ring 25 about the member 21 is arranged to be prevented by means of the engagement of an outwardly extending key 31 formed integral with the member 21 in an axially directed key slot 27 provided in the ring, whereby the surface 18 slidably and frictionally engages the top surface of the ring, and the latter is held in fixed engaged relation with the spring. A guard for 20 the spring is preferably provided, such guard being here shown in the form of a cylindrical shell 28 arranged to rest directly on the surface 19 outwardly of the flange 24.

I claim:

35 1. In combination with a standard, an arm arranged to extend generally radially from the standard and provided with spaced portions arranged to slidably receive said standard, a collar slidably fitting and adjustably 40 fixed to said standard between said portions, a ring encircling said standard and collar between said portions, and means operative to simultaneously and resiliently engage said collar and ring with different of said portions.

45 2. In combination with a standard, an arm arranged to extend radially from said standard and provided with spaced portions arranged to receive said standard, a collar adjustably fixed to said standard between said portions, a ring encircling said standard between said portions and movable axially of said collar, a helical compression spring carried by said collar and operatively engaged 50 between the collar and ring whereby said collar and ring are resiliently and frictionally engaged with different of said portions, and cooperating means on said collar and ring engageable to prevent relative rotations 55 between the collar and ring.

60 3. In combination with a standard, an arm arranged to extend generally radially from said standard and provided with spaced portions arranged to slidably and rotatably receive said standard, a pair of members encir-

cling said standard between said arm portions, means operative to simultaneously and resiliently engage each of said members with a different one of said portions, and cooperating means on said members engageable to prevent a relative rotation thereof.

In testimony whereof, I affix my signature.

MILES F. DEACH.
